HAND PIECE FOR POWER DRIVEN TOOLS

John Hyde, Chicago, Ill.

Application June 28, 1938, Serial No. 216,340

2 Claims. (Cl. 279—35)

This invention relates to hand pieces for power-driven tools and has for the primary object the provision of an efficient and inexpensive device of this character which will provide a coupling between a power driven flexible shaft and a tool of any kind, such as a brush employed for cleaning teeth and which may be easily and quickly operated to establish a driving connection between the shaft and tool and to interrupt said drive when desired and to permit the easy removal of the tool when desiring to clean the latter or to substitute one tool for another.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a side elevation showing a hand piece constructed in accordance with my invention and illustrating the hand piece connecting a tool to a flexible shaft of a power source.

Figure 2 is a sectional view taken on line 2—2 of Figure 1, with the hand piece actuated to establish a drive between the flexible shaft and the tool.

Figure 3 is a side elevation partly in section showing the hand piece positioned to release the driving connection between the flexible shaft and the tool.

Figure 4 is a sectional view taken on line 4—4 of Figure 2.

Figure 5 is an end view illustrating a coupling sleeve.

Figure 6 is a vertical sectional view showing the coupling sleeve.

Figure 7 is a side elevation illustrating a mandrel.

Referring in detail to the drawings, the numeral 10 indicates a hand piece, the outer face of which may be knurled and is internally screw threaded, as shown at 11. The hand piece 10 is in the form of a sleeve and is provided at one end with an inwardly extending flange 12 acting as a stop for a hand piece 13, the latter being in the form of an elongated tube. A plug 14 having a bore 15 is threaded into the hand piece 10. One end of the bore 15 is enlarged to form a socket 16 for the reception of one end of a flexible shaft housing 17, the flexible shaft being indicated by the character 18. The housing 17 and the flexible shaft are connected in any well known manner to a power source 19 which in this instance is

in the form of an electric motor. However, any other type of power source may be employed.

A bearing sleeve 20 is mounted in the hand piece 13 at one end thereof and has a frictional fit therewith with one end extending outwardly of the hand piece 13 and received within the flanged end of the hand piece 10. The bearing sleeve carries set screws 21 for removably securing in one end of the bearing sleeve a bearing block 22 having a bore aligning with the bore 15 of the plug 14 so as to permit the flexible shaft 18 after extending through the bore 15 to extend through said bearing block 22.

A coupling element 23 is journaled in the bearing sleeve 20 with one end resting on the bearing block 22 and if desired anti-friction means may be placed between the bearing block and the coupling element 23. One end of the coupling element 23 has a socket to receive the end of the flexible shaft 18, the latter being secured in the socket by a set screw 24 carried by the coupling element 23 and the other end of said coupling element has a socket 25 provided with angularly related faces to match angularly related faces formed on a shank 26 carried by the butt end 27 of a mandrel 28. The butt end 27 of the mandrel 28 includes an enlarged bearing portion 29 resting against one end of the coupling element 23 and an internal shoulder 30 formed in the bearing sleeve 20. A packing gland 31 is carried by the bearing sleeve and contacts the butt end 27 of the mandrel. A portion of the mandrel 28 is tapered with the taper extending towards the free end of the mandrel and formed on the tapered portion is a plurality of spaced ribs 32 also tapered towards the free end of the mandrel.

A combined stop and guide collar 33 is mounted in the hand piece 13 through which slides the tapered portion of the mandrel 28. A plug 34 is removably mounted in the end of the sleeve 13 and has a bore through which a shank 35 of a tool 36 extends. The tool in this instance is in the form of a brush, as clearly shown in Figure 1.

The bearing sleeve 20 has a groove 37 in which operates a set screw 38 carried by the hand piece 13 whereby the latter may be slid on the bearing sleeve towards and from the hand piece 10. The bearing sleeve tightly fits within the hand piece 10 and is relatively stationary with respect thereto.

Companion chuck jaws 39 are arranged in the hand piece 13 between the combined stop and guide collar 33 and the plug 34. Each jaw 39 has a curved face 40 to contact with the shank 35.

- of the tool after the shank passes through the plug 34. Each jaw has a comparatively straight face 41 to engage with ribs on the mandrel 28 when the latter is inserted between the jaws.
- 5 The jaws are connected together for a rocking motion relative to each other by a pin 42 engaging rounded walls 43 of openings arranged opposite to each other in the jaws so that when the mandrel is forced between the straight faces
- 10 41 of the jaws the latter will rock on the pin and cause the curved faces of the jaws to grip the shank of the tool, thereby establishing a detachable driving connection between the mandrel and the shank of the tool. It is to be understood that the jaws are freely rotatable within the hand piece 13.

In operation, with the butt end 27 of the mandrel connected to the flexible shaft, as described in detail, and with the motor in operation, and 20 with the parts positioned as shown in Figure 3, the operator slides the hand piece 13 towards the hand piece 10. The sliding movement of the hand piece 13 as described brings the jaws into engagement with the tapered portion of the 25 mandrel causing said jaws to rock on the pin 42 and thereby tightly grip the shank of the tool. A movement of the hand piece 13 away from the hand piece 10 disconnects the mandrel from the jaws also freeing the jaws from the shank of the tool so that the latter may be pulled out of the jaws if desired.

It is believed that the foregoing description, when taken in connection with the drawings, will fully set forth the construction and advantages 35 of this invention to those skilled in the art to which such invention relates so that further detailed description will not be required.

Having described my invention, what I claim is:

- 40 1. In a device of the class described an elongated tubular handle member having an opening at one end for receiving the shank of a tool and a chamber therein with which said opening communicates, elongated longitudinally extending 45 jaw members rotatably supported in the

chamber, a fulcrum member engaged by intermediate parts of the jaw members, a supporting member by which the handle member is supported for sliding movement longitudinally, and a mandrel rotatably supported by said supporting member and adapted to be rotated, said mandrel having a tapered end extending into the chamber, when the handle member is in retracted position, and extending between the adjacent ends of the jaw members to spread said ends apart and to cause the opposite ends to grip a tool shank passed through the openings and said end of the mandrel frictionally engaging the said adjacent ends of the jaw members to cause rotary movement of the jaw members with the mandrel, said tapered end of the mandrel moving out of the chamber and out of engagement with the jaw members when the handle member is projected.

2. In a device of the class described, a supporting member, an elongated tubular handle member having one end portion slidably fitting over a portion of the supporting member, a mandrel having one end rotatably supported by said portion of the supporting member with said mandrel located in the handle member and said mandrel adapted to be rotated, a chamber in the tubular member adjacent its other end, said other end having an opening therein which communicates with the chamber and is adapted to receive the shank of a tool, a pair of jaw members rotatably arranged in the chamber, a fulcrum member engaged by intermediate portions of the jaw members for rocking movement of the jaw members, the free end of the mandrel being tapered and roughened and said end entering the chamber and passing between the inner ends of the jaw members, when the handle member is retracted on the supporting member and said free end of the mandrel being withdrawn from the chamber and from between the jaw members when the handle member is projected on the supporting member.

JOHN HYDE.
